UNITED STATES PATENT OFFICE.

CHARLES HENRY SEWALL, OF CHICAGO, ILLINOIS.

UNDERGROUND CONDUIT FOR ELECTRIC CONDUCTORS.

SPECIFICATION forming part of Letters Patent No. 603,745, dated May 10, 1898.

Application filed May 8, 1895. Serial No. 548,613. (No model.)

To all whom it may concern:

Be it known that I, CHARLES HENRY SEWALL, a citizen of the United States, residing in Chicago, in the county of Cook and State 5 of Illinois, have invented certain new and useful Improvements in Underground Conduits for Electrical Conductors, of which the following is a specification.

My invention relates to that class of structures which are composed of sections of pipes joined end to end and laid in multiple to form a group of ducts into which can be drawn electrical conductors or cables; and the objects of my improvements are to create a conduit structure which is practically without joints and which has great strength and durability, and also to provide ducts of a shape better adapted to meet requirements than either the round or square ones now in use. 10 Referring to the drawings, Figure 1 is a cross-sectional view showing my conduit as a whole and ready for use. Fig. 2 is a view in perspective of a single section G of the upper part of the duct. Fig. 3 shows a cross-section of G with wire-cloth embedded therein; Fig. 4, a wire bridge F, used for joining sections G; Fig. 5, sections G G joined by bridge F.

The same letters represent the same parts 15 in the different views.

A, Fig. 1, represents the soil filling a trench in which conduit B is buried.

C is the area bounded by a broken line indicating the space and position in a duct 20 which will be occupied by a cable of electrical conductors.

G is an arch-shaped inverted channel which is the upper portion of a duct in the conduit, and g is wire-cloth embedded in arch G.

F is a wire-cloth bridge used to connect sections G G.

Referring to Fig. 3, the letter r is so placed as to show the uppermost point or apex of inside of arch G. t is the lowermost point or 25 duct-floor line. s is a point half-way between r and t. The horizontal line x s is the line of meeting of the straight sides of arch G with the semicircular top or roof. The line m n is horizontal through the center of cable C when 30 the latter is lying upon duct-floor line t.

It is a fact that the bond of iron and concrete, whereby the iron acts as a tension and

the concrete as a compression member, affords a structural strength much greater than if the concrete is used alone. It is necessary, 55 however, that the tension member shall be immovable. Wire in the form of cloth (a rectangular mesh being preferable) will not slip through set concrete, and repeated experiments have shown that the full compressive strength of the concrete and nearly the 60 full tensile strength of the iron wires in the warp are the properties of a composite made by embedding wire-cloth in a concrete of hydraulic cement and sand. 65

The arch-shaped channels shown in the drawings in sections about six feet in length are laid in multiple on a smooth flat floor made continuous between manholes, said floor being of such horizontal dimension as is required for the number of ducts in each layer. The arches are then fixed in place by a cement concrete which fills the spaces between them and covers their tops; and this covering can be leveled and smoothed to form a 70 floor upon which a second series of arches 75 may be laid. The process continues, layer upon layer, until the required number of ducts is formed.

At this writing underground conductors of 80 electricity are almost invariably, either singly or in groups, inclosed in a lead sheath, making them air and moisture proof. For convenience in making and handling the lead-covered cable is round in cross-sections. 85 Good practice admits but one cable in each duct.

It is desirable that underground conduits should be formed from materials that are 90 proof against corrosion by chemical action, that have sufficient hardness to turn off accidental strokes of digging-tools, and the necessary strength to resist pressures caused by heavy weights on street-surfaces, and as the laying of sewers, gas-pipes, and water-mains 95 and their surfaces is a frequent source of trouble (by reason of workmen undermining conduits) there should be combined with the above qualities both compressive and tensile strength to resist shearing forces. It may be 100 said also that while strains upon conduits are mainly from downward pressures those in other directions are not unusual and should be carefully considered.

It will be seen that the form of duct shown in the drawings (see Figs. 1 and 2) and the material of which the herein-described structure is made are both well adapted to conduit work.

The floor of my duct is preferably smooth and flat. It can be made slightly concave. The upper part has vertical sides surmounted by a semicircular roof, the radius of the inner side surface of said roof (7 s, Fig. 3) being the same as the height of the straight sides, (s t, Fig. 3.) The advantages of this shape are that it combines the roominess of a flat floor with the supporting strength of the perpendicular walls under an arched roof.

The support given by the arches is much greater than if the ducts were round, square, or semicircular in form. The space occupied is exactly the same as if the ducts were round or square and is but one-half of what would be occupied by an opening in the form of a semicircle. For instance, if a semicircular opening is needed to be three inches in height in order that a round cable of, say, two and one-half inches diameter may conveniently be drawn into it then its radius will be three inches and the width of opening at base will be the diameter or six inches, while with my arches the width at base will be but three inches. It can also be said that if the height of the straight sides is greater than the radius of the semicircular roof space is wasted, because if there be drawn into the duct a round cable having a diameter a little less than the width of the duct there will be a proportionally-greater space between the top side of the cable and the apex of the arch, which additional space will increase the size and consequent cost of the structure and will serve no useful purpose. On the other hand, if the height of the straight sides is less than the radius of the roof then the vertical dimension will be insufficient to contain a cable having a diameter proportioned to the horizontal distance between the perpendicular sides. Thus the exact condition of straight sides of the same height, as is the length of radius of roof surmounting them, is the most economical of space and in every way the best adapted to the function of a conduit-duct, although I do not limit myself to this specific preferred structure.

In a pipe having a circular cross-section a cylindrical cable, which in practice is more or less crooked, will wedge itself and bind against the sides of the pipe and its covering be subjected to injury from abrasion. Hence a further advantage of my duct form is that a cable which is being drawn into it can have as much sidewise swing as it would have in a square duct, for as the round cross-section of the cable must necessarily be somewhat smaller than the opening through which it is drawn then the greatest chord of said round cross-section, the diameter, (see line m n, Fig. 3,) will come below the line of greatest height of the perpendicular sides of the duct, (see

line x s, Fig. 3,) and consequently the cable cannot come into contact with any point on the surface of the semicircular roof. Again, the arched roof, while in no way impeding the movements of the cables, is much stronger than the flat roof of a square duct, and the perpendicular supporting-sides upon a flat floor make a much stronger foundation than the semicircular one which contributes the upholding strength of a round pipe.

Another feature of my invention is that the device herein shown escapes the greatest peril that has heretofore menaced all conduits laid in sections—viz., the settling and breaking of the structure at the joints. As my duct-floors are continuous for an entire division the weakness at joints is overcome—that is to say, the lower part or floor of the duct is jointless and underlies the upper or sectional part. A wire bridge F, Figs. 3 and 4, is used to bind together the upper sections.

Referring to Fig. 5, a strain upon any part of the conduit will be resisted by the tensile strength of the wires in bridge F, and if the mesh of the wire-cloth be rectangular in form (as I prefer and have shown in the drawings) those wires which resist strain will be anchored by reason of the wires which run across them being unable to move through the set concrete, the holding power of each "cross-wire" or "anchor" being equal to the compressive strength of the hardened concrete in which it is embedded.

Still further, to strengthen the conduit there may be placed in the foundation and in each successive floor wire-cloth laid flat. The lengths may be joined by overlapping, as concrete will bond the joint; but it will be possible to weave the cloth in continuous lengths, which shall reach from manhole to manhole without joints. Even if the arches are not wired the floor-wires alone will insure a proportionally strong structure.

The conduit structures herein described will resist strains from any direction. In any way that the conduit be distorted by strain the great tensile strength of iron wires will be brought into tension in one half of its body and the equally great compressive strength of cement concrete be brought into compression in the other half.

For the material in the body of the conduit I prefer a concrete of hydraulic cement and sand; but other materials can be used—bituminous concrete, for instance. I do not limit myself in this particular.

It is not essential that the sides should be perpendicular, nor is it essential that the floor should be flat, and both may be varied as desired.

In Fig. 1 I have shown the foundations of the two lower tiers of sections as provided with open binders or sheets G' G' of wire-cloth or similar material to impart tensile strength to the concrete. These binders may be placed in some or all of the foundations or bodies of surrounding material, as desired.

Any of the departures just mentioned, or similar ones, which, however, embody the principles of my conduit, are, I claim, equivalents and within the scope of this patent.

5 Again, in considering the novel feature of a conduit-duct having a smooth continuous floor, upon which are laid inverted channels in sections, which are then rigidly and permanently joined, I do not limit myself to the 10 particular duct shape herein described. The inverted sectional channel on a continuous floor is a proportionally desirable device, whether the shape of the sections be arched, rectangular, or semicircular, or whether the 15 inverted channel-sections be made single to complete a single duct.

I claim—

1. As a conduit for electrical conductors a plurality of inverted channels made in separate and single sections, said sections resting upon a flat foundation-floor, which, with the inverted channels, form duct-openings; and the said channels supporting other floors each one sustaining its complement of inverted 25 channels whereby the conduit can be made of any width or height and contain any number of ducts.

2. A conduit for drawing in and drawing out electrical conductors consisting of an inverted channel made in sections laid end to end and resting upon a flat floor which forms the lower side of said duct, the said floor being composed of a material plastic when first made but setting to hardness, plastic setting 30 material being also used to form supporting sides and a covering-top whereby the floor, sides and top become an integral support for the sectional channel which serves to hold it rigidly in position.

3. A conduit for electrical conductors consisting of a foundation having a floor formed on the surface thereof, and an inverted channel-section superimposed upon said floor which completes the duct, said channel being 45 composed of material plastic when first made but which sets to hardness and an open frame or binder incorporated into the material of said inverted section and conforming to the shape of the inner wall thereof, substantially 50 as described.

4. A conduit for electrical conductors consisting of a smooth flat floor of indefinite width upon which are placed side by side a plurality of ducts, each duct being formed by super-

imposing upon said floor inverted channels 55 in sections placed end to end, the said sections of each duct being rigidly and permanently joined at their ends as well as with the sections of other ducts at their sides whereby the whole structure is bonded together. 60

5. As a conduit for electrical conductors the section G laid end to end upon a flat floor and joined at ends by bridges F; the sections G, bridges F and floor being all joined by a setting cement whereby the metallic frame- 65 works g are anchored and caused to contribute tensile strength to the structure as a whole.

6. A conduit-duct for electrical conductors consisting of a smooth flat floor of indefinite length, said floor being a composite made by 70 embedding a metallic frame in cement, concrete or other like plastic material whereby the concrete acts as a resistance to compressive strain and the iron wires as resistance to tensile strain; and upon which are superimposed in sections inverted channels placed end to end. 75

7. In an underground conduit, the combination with a foundation of concrete, or similar material, having a floor formed on the surface thereof, of an inverted channel resting upon said floor whereby the floor forms the bottom of the conduit, and a body of concrete, or similar material, inclosing and surrounding said inverted channel and formed integral with the concrete constituting the foundation, substantially as described. 80

8. In an underground conduit, the combination with a foundation of concrete, or similar material, having a floor formed on the surface thereof, of an inverted channel placed upon said floor so that the floor forms the bottom of the conduit, a body of concrete, or similar material, inclosing and surrounding said inverted channel and formed integral 85 with the concrete constituting the foundation, said second body of concrete having a floor formed on the surface thereof, a second inverted channel resting thereon, and a third body of concrete, or similar material, inclos- 90 ing and surrounding said second inverted channel and formed integral with said second body of concrete, substantially as described. 100
